(57) CLAIM

The ornamental design for a multi-piece face plate, as shown and described.

DESCRIPTION

FIG. 1 is a perspective view of a multi-purpose face plate showing my new design;

FIG. 2 is an enlarged top plan view thereof;

FIG. 3 is a bottom plan view thereof;

FIG. 4 is a front view thereof;

FIG. 5 is a rear view thereof;

FIG. 6 is a left side view thereof; and,

FIG. 7 is a right side view thereof.

The broken line showing on FIGS. 1-3 and 6-7 is for illustrative purposes only and forms no part of the claimed design.
